UNITED STATES PATENT OFFICE

GEORGE SHERWOOD, OF MINNEAPOLIS, MINNESOTA, ASSIGNOR TO G. W. VAN VUREN,
OF CHIPPEWA FALLS, WISCONSIN

WASHBOARD

Application filed June 5, 1929. Serial No. 368,621.

This invention relates to wash boards of the type used for cleaning clothes by hand rubbing the same thereon, and the primary object is to provide a device of that character which is efficient and practical in construction and which presents several novel features over prior art devices that have come to my attention. More particularly the invention herein disclosed presents several distinct improvements over the somewhat similar type of wash board shown in Patent No. 1,385,442 issued to W. P. Griffith et al. on July 26, 1921. The device shown in said patent is directed broadly to the feature of incorporating in a wash board longitudinally disposed series of alternated rubbing strip and brush elements, which features, by license arrangements with the patentees, have been carried into the device herein disclosed. The particular novel features and specific advantages of the present device over that shown in said patent will be fully disclosed in the course of the following specification, reference being had to the accompanying drawings, wherein:

Fig. 1 is a plan elevation of my improved wash board, fractional portions being broken away for purpose of illustration.

Fig. 2 is a sectional elevation on the line 2—2 in Fig. 1.

Fig. 3 is a cross section on the line 3—3 in Fig. 1.

Fig. 4 is a bottom end view of the board.

Fig. 5 is an enlarged detail section showing the flange connection between the back plate and soap tray of the board.

Fig. 6 is an enlarged detail section of the channel member at the lower end of the wash board, or as seen substantially on the line 6—6 in Fig. 4.

Referring to the drawings more particularly and by reference characters, 7 and 8 designate the side bars of the wash board, which bars are preferably provided with tapered lower ends and flared upper ends, as shown in Fig. 2.

At their upper ends the bars 7 and 8 are connected by a cross rail 9, the ends of which are seated in suitable sockets in the bars, and which is retained or held in position by the

opposed clamping action of the side bars as effected by a pair of bolts 10 and 11. As will presently be described these bolts 10 and 11 form the sole securing means for holding all the parts of the entire device in a rigid assembled condition, which not only greatly simplifies the manufacture thereof, but eliminates nails or rivets, and provides a simple and practical method for replacing broken or worn out parts. The bolts each have a head at one end and a nut at the other end, to which small wrenches or pliers may be applied to effect tightening or removal of the bolts.

Disposed between the rail 9 and the bolt 10 is a soap tray 12, formed of sheet metal and slightly curved, with a ledge 13 at its lower end to serve as a soap bar support. At its upper end the metal member 12 is curved about the rail 9 (see Fig. 2) and has its end 14 imbedded therein. Thus the metal and wood not only reinforce each other but the metal substantially covers the entire rail to present a smoother completed surface and as the wooden rail is not exposed there is no opportunity for slivers to catch in fabrics being cleaned or in the operator's hands.

The lower end of the member 12 not only serves to conceal the rod or bolt 10, from above, and comprises a soap supporting ledge, but terminates in a fold or crease 15, which grips the depending ledge 16 of the upper horizontal flange 17 of a back plate 18 (see Fig. 5). Thus there is a reinforced bracing engagement between the two members 12 and 18, and no raw metal edges are exposed at the upper end of the rubbing section of the device. The lower end of the back plate 18 is disposed or secured within the rear flange of a channel shaped, sheet metal cross bar 19, the longitudinal edges of which are inturned, as shown in Fig. 6, so that no raw edge will be exposed. The ends of the channel bar 19 are provided with depending perforated lugs 20, through which the supporting rod 11 is extended.

At its sides the back plate 18 is provided with inturned flanges 21, abutting the side bars 7—8, and these flanges have their edges outwardly bent and imbedded in grooves in

the bars, as shown at 22 in Fig. 3, to thereby brace the back plate against backward bowing when the device is in use. As a result of the construction thus described it will be seen that the back plate is braced at all four sides against rubbing pressure upon the cleaning surface. The plate proper, however, is rendered still more rigid by being provided with a series of longitudinally disposed shallow channels or flutes 23. These flutes, which are transversely spaced, not only reinforce the plate, but also provide seats for certain of the cleaning members, as will now be set forth.

The face of the wash board presents a series of longitudinally disposed brushes, between which are arranged a series of corrugated strips, the levels of which are slightly below the levels of the brush bristle ends. The corrugated strips or faces 24 comprise the exposed faces of a plurality of channel shaped members 25, formed of sheet metal and with their edges abutting the back plate 18 at the sides of the flutes 23. Within each of the members 25 is arranged a somewhat similarly formed or channel shaped member 26. These members each resemble a square tube element the under side of which is slotted or open.

The brush blocks or backs 27 of the brushes are disposed between the lower sides of the members 25, so as to substantially fill these spaces, and the tufts 28 project upwardly, as noted, to a point slightly above the level of the corrugated faces 24. It will also be noted that the upper (i. e., exposed) portions of the channel members 25 are flared out so as to completely fill the spaces between the brush bristles, of each pair of brushes, and that while the members 26 are shallower than the members 25 the valleys of the corrugations will bear upon the surface of the inner channel so that the rubbing metal surface will be very rigid. The brushes as well as the members 25 and 26 are of course all rigidly mounted by having their ends projected into the opposed channels at the upper and lower ends of the back plate.

In addition to the matters of rigidity, simplicity and practicability the structure as above described and particularly as illustrated in Fig. 3 results in a further advantage, namely, that when the brush blocks 27 swell, from being subjected to the wash water, they cannot distort or damage any other part of the device. Thus the resiliency of the channel members 25 and 26 is always ample to permit the brush backs to expand and contract under varying moisture conditions, and consequently there can be no substantial swelling strain imparted to the side bars or tie bolts of the main frame as would for instance be the case with the device as shown in the above noted Griffith et al. patent.

It may here be noted that the soap tray 12-13 is provided with drain holes 29 (Fig. 5), and that the channel member 19 is similarly provided with drain holes 30 (Fig. 4).

From the foregoing description, considered in conjunction with the drawings, it will be seen that I have provided a practical construction of wash board, all the parts of which are held together in assembled position by the two bolts or bars 10 and 11. It will also be apparent that to replace any of the elements 25, 26, or 27 it is not necessary to disassemble and reassemble the entire device, but any one of these elements can be quickly and easily substituted by temporarily removing the bolt 11 and channel member 19.

It is understood that suitable modifications may be made in the structure as disclosed, provided such modifications come within the spirit and scope of the appended claims.

Having now therefore fully illustrated and described my invention, what I claim to be new, and desire to protect by Letters Patent is:

1. A wash board comprising side bars, tie bolts connecting the side bars, a series of longitudinally disposed members having exposed rub surfaces, disposed between the side bars, and a series of brushes fixed in blocks disposed between said members, said members being transversely yieldable under pressure to permit expansion and contraction of the brush blocks.

2. A wash board comprising side members, a back plate connecting the members and provided at its upper end with a transverse channel portion, a channel member at the lower end of the board, longitudinally disposed rubbing strips and block carrying brushes having their ends secured in said channel portion and channel member, said strips being yieldable to allow for swelling of the brush carrying blocks disposed there-

3. A wash board having a rubbing surface formed by corrugated rubbing members and brush bristles disposed therebetween, and blocks to carry said bristles, said rubbing members being transversely flexible under pressure whereby they will yield to swelling action of the brush blocks, to prevent breakage or distortion of any other part of the board.

4. A wash board having a rubbing surface formed by corrugated yieldable channel shaped rubbing members and brush bristles disposed therebetween, and longitudinally disposed yieldable reinforcing elements disposed within the rubbing members.

5. A wash board comprising side bars, a sheet metal back plate disposed between the bars and having flanged side portions secured thereto, a series of rubbing members

carried by the back plate, and channel members at the upper and lower ends of the back plate to retain said rubbing members.

6. A wash board comprising side bars, a sheet metal back plate disposed between the bars and having flanged side portions secured to the bars, a series of rubbing members carried by the back plate, a reinforcing flange projecting forwardly from the upper end of the plate, and a soap tray disposed between the side bars above the plate, said soap tray having a depending flange portion folding under and gripping a portion of said back plate reinforcing flange.

15 7. A wash board comprising a pair of side bars connected by tie bolts extending from one to the other, devices carried between the bars to present a rubbing surface, a sheet metal back plate carried between the side bars 20 to support the said devices, and a sheet metal soap tray between the upper ends of the bars, the lower end of said tray being folded over and clinched against the upper edge of the back plate.

25 8. A wash board comprising a pair of side bars connected by tie bolts extending from one to the other, devices carried between the bars to present a rubbing surface, a sheet metal back plate carried between the side bars 30 to support the said devices, and a sheet metal soap tray between the upper ends of the bars, the lower end of said tray being folded over and clinched against the upper edge of the back plate, and the upper end of the tray 35 being provided with lateral extensions for locking engagement with the side bars.

Signed at Minneapolis, in the county of Hennepin, and State of Minnesota.

GEO. SHERWOOD.
